UNITED STATES PATENT OFFICE.

ALBERT DELAS, OF PARIS, FRANCE, ASSIGNOR TO DELAS CONDENSEE CORPORATION, OF NEW YORK, N. Y., A CORPORATION OF DELAWARE.

METHOD OF AND APPARATUS FOR INCREASING THE VACUUM OF TURBINES.

Application filed October 19, 1920, Serial No. 417,990, and in France November 22, 1919.

The invention forming the subject matter of the present application relates to steam turbines and has for its principal object to provide a method, and means for carrying such 5 method into practice, of reducing the drop in pressure between the exit end of the turbine blades, or vanes, and the condenser.

The use of higher and higher expansions in the design and operation of steam turbines 10 and consequently the use of very high vacuums at the exit of the last blades, in order considerably to diminish the specific consumption of the turbines, has led to a difficult problem. It has been found that the drop of pressure 15 between the exit of the blades and the condenser has a considerable detrimental influence upon the efficiency of the turbine.

Attempts have been made to reduce this drop in pressure by designing or making the 20 dimensions of the steam passages or channels such as to reduce the average flow of the steam or other fluid therethrough. Although this expedient is efficacious for a quiet steam flow, progressing at even speed and in parallel 25 paths, experience has shown that it is much less efficient for steam which issues from the turbine blades in an agitated condition and in which there are whirls and eddies due, among other causes, to the changes of direction 30 of flow to which it is subjected in the steam collector.

Experiments made on steam ejectors forming the subject matter of my French Patents 488,782, of Feb. 4, 1918, and 491,620, of Sept. 35 6, 1918, and my copending U. S. applications, Ser. Nos. 260,600½, 260,601½ and 324,391, have shown that cooling of the walls of the diffuser causes the suppression of eddies, by the fixation of the incident molecules or particles, with a consequent increase of efficiency. This increase of efficiency is greater than 40 would be expected in view of the small quantity of steam actually condensed.

The observations made in connection with 45 the important improvements in ejectors led to the solution of the problem of reducing the drop in pressure above mentioned in connection with turbines. I solve this problem in the steam collectors and if desirable or necessary 50 in the exhaust pipes by cooling the walls thereof.

The method may be best explained and understood by describing one of the forms of apparatus which may be employed to carry 55 the same into practice. Referring to the

drawings which illustrate what I now consider a preferred form of the invention:

Fig. 1 is a somewhat diagrammatic sectional detail elevation illustrating the invention as applied to a steam turbine. 60

Fig. 2 is an end elevation of the apparatus shown in Fig. 1.

The prime mover or turbine illustrated comprises a stator 1, provided with blades or 65 vanes 2, and a rotor 3 provided with blades or vanes 4. Steam, or other elastic motive fluid, may be supplied to the turbine in any of the well known ways and, after having passed through the stages of the machine, passes into the exhaust steam collector 5. From the collector or chamber 5 the steam passes to a condenser 10 through the discharge opening 6 and any suitable connections. I condense the steam which impinges upon the walls of the collector 5 by cooling the walls of the latter. 70 One means for accomplishing this result may be constructed substantially as follows:

The steam collector or chamber 5 is provided with a double envelope or jacket 7 in which is established a circulation of cold 75 water (or other cooling fluid) on all of its surface or only on the parts directly impinged by the stream of steam leaving the blades of the turbine. The water or cooling fluid may be introduced at 8 and discharged at 9 or 80 vice versa.

This circulation may be extended to the piping or conduit connecting the turbine to the condenser, should the shape of said pipe or conduit be such as to produce or tend to produce 85 eddies.

The walls which are cooled should preferably be constructed of metal, of good heat conductivity such as aluminum, bronze, etc.

By virtue of the method and means above 90 described the drop in pressure from the steam exit at the blades of the turbine to the condenser is effectively and greatly reduced. What I now consider the theory of operation 95 of my invention will be clearly apparent from the foregoing description in view of the disclosure in my copending applications and patents above mentioned.

What I claim is:—

1. In combination, a condenser, a turbine 100 adapted to be supplied with condensable elastic motive fluid and to discharge the same into said condenser, an exhaust fluid collector located between the turbine and condenser, and means whereby a cooling liquid is passed in 105 110

contact with at least a portion of the walls of said collector.

2. In combination, a condenser, a vapor-actuated turbine provided with means for conveying its exhaust to said condenser, and means forming a cooling jacket around at least a portion of said first named means.

3. In combination, a condenser, a vapor-actuated turbine provided with means for con-

veying its exhaust to said condenser, and means forming a cooling jacket around at least a portion of said first named means, the inner wall of said jacket being of metal of comparatively high heat conductivity.

In testimony whereof I hereto affix my sig. 15
nature.

ALBERT DELAS.
